[57] CLAIM

The ornamental design for a header for a merchandising display stand, as shown and described.

DESCRIPTION

FIG. 1 is a perspective view of a header for a merchandising display stand or the like showing my new design; the broken lines indicate environmental structure;

FIG. 2 is a bottom plan view thereof;

FIG. 3 is a top plan view thereof;

FIG. 4 is a side elevational view thereof; and

FIG. 5 is a front elevational view thereof.

FIG. 3

FIG. 5
